UNITED STATES PATENT OFFICE.

JOSEPH E. LOEFFLER, OF ST. LOUIS, MISSOURI.

LIFTING AND SWINGING SUPPORT FOR RAILWAY MOTOR-CARS.

1,383,832.

Specification of Letters Patent.

Patented July 5, 1921.

Application filed October 30, 1919. Serial No. 334,592.

To all whom it may concern:

Be it known that I, JOSEPH E. LOEFFLER, a citizen of the United States, residing at St. Louis, Missouri, have invented a certain 5 new and useful Improvement in Lifting and Swinging Supports for Railway Motor-Cars, of which the following is a full, clear, and exact description, such as will enable others skilled in the art to which it apper- 10 tains to make and use the same, reference being had to the accompanying drawings, forming part of this specification.

My invention relates generally to railway motor cars and more particularly to 15 an attachment for motor cars whereby the same may be readily lifted to enable the car to be turned end for end, thereby reversing its position upon the railway track or for 20 the purpose of permitting the car to be turned and positioned upon the rails of a crossing track.

It will be understood that motor cars driven by internal combustion engines or the like are now in general use upon rail- 25 ways for inspection purposes and for carrying workmen, tools, and supplies to points on the track which require repairs. The weight of these motor cars preclude their being lifted by workmen and turned around 30 or placed upon crossing tracks, and it is the principal object of my invention to pro- 35 vide a relatively simple lifting mechanism that is positioned upon the car and by means of which the operator or driver of the car may readily and with comparatively little effort lift the motor car and swing it into reverse position or into position upon the rails of a crossing track.

Further objects of my invention are, to 40 provide a motor lifting mechanism which comprises but relatively few operating parts, the same occupying relatively little space upon the motor car and capable of being readily manipulated to lift the car 45 and parts carried thereby.

With the foregoing and other objects in view, my invention consists in certain novel features of construction and arrangement of parts, hereinafter more fully described 50 and claimed, and illustrated in the accom- 55 panying drawings, in which—

Figure 1 is a cross sectional view of the frame of a railway motor car and showing my improved lifting mechanism positioned 55 thereupon.

Fig. 2 is a vertical section taken approximately on the line 2—2 of Fig. 1.

Fig. 3 is a sectional view similar to Fig. 1 and showing the lifting mechanism lowered into position to engage the surface of 60 the road bed between the track rails in order to lift the motor car.

Fig. 4 is a horizontal section taken approximately on the line 4—4 of Fig. 3.

Fig. 5 is an enlarged horizontal section 65 taken approximately on the line 5—5 of Fig. 3.

Fig. 6 is an enlarged vertical section taken approximately on the line 6—6 of Fig. 3.

Fig. 7 is an enlarged horizontal section 70 taken approximately on the line 7—7 of Fig. 1.

Referring by numerals to the accompanying drawings which illustrate a practical embodiment of my invention, 10, 10 designate the side rails of the lower frame of a railway motor car, 11 the side rails of the upper framework of said car, and 12 the platform that is supported upon said upper rails.

Secured in any suitable manner to the rails 10 and 11 are posts or uprights 13 and secured to said uprights by means of brackets 14 are vertically disposed channel guides 15. Arranged to slide vertically be- 80 tween these channel guides is a substantially rectangular frame comprising a pair of up- right side members 16, a top rail 17, and a bottom rail 18, said top rail being provided at its center with a bearing block 19.

Rigidly fixed to the central portion of the lower rail 18 is a laterally projecting arm 20 in the outer portion of which is formed a slot 21, and loosely mounted in the latter is the upper end of a pin or bolt 22 on the 95 lower end of which is rotatably mounted a foot plate 23. Fixed in any suitable manner to the top rail 17 is the lower end of a lifting bar 25 that projects upwardly through a suitable opening in platform 12 and the 100 upper end of said bar being formed into a handle 26. Formed in this lifting bar are apertures 27 and arranged for sliding move- 105 ment in suitable bearings 28 on the platform 12 to the side of the opening through which the bar passes is a bolt 29 that is adapted to enter any one of the apertures in said lifting bar and thus lock the sliding frame 16 in either elevated or lowered position.

Secured in any suitable manner to the up- 110

per side rails 11 of the motor car frame and adjacent to the upper ends of uprights 13 are horizontally disposed pairs of rails 30 which serve as supports and guideways for a transversely disposed sliding bar 31. Passing through a threaded aperture in the center of this bar is a vertically disposed threaded rod or shaft 32, the same extending upwardly through a longitudinally disposed slot 33 formed in platform 12 and carried by the upper end of said threaded rod is a hand wheel 34.

Screw-seated upon the upper portion of the threaded rod is a nut or collar 35 through which passes a set screw 36, which latter when tightened, will lock said nut or collar in its adjusted position upon the threaded shaft.

While not in use, the various parts of my improved motor car lifting mechanism occupy the positions illustrated in Figs. 1 and 2. The vertically sliding frame comprising the parts 16, 17 and 18 is held in its elevated position by engagement of locking bolt 29 in the lower one of the apertures 27 in the lifting bar 25 and bar 31 is moved into a position to one side of the vertical plane occupied by the sliding frame and threaded rod 32 is screwed downward in said bar 30 and being held in such position by tightening set screw 36 in nut or collar 35.

To reverse the position of the motor car upon the track rails or to shift its position so that it can be placed on the rails of a crossing track, locking pin 29 is withdrawn from the aperture in which it is positioned and the sliding frame is permitted to move downward until the foot plate 23 rests upon the road bed. Threaded rod 32 is now manipulated so that it is moved upwardly through bar 31 until its lower end occupies a horizontal plane that is occupied by the bearing block 19 after which rod 32 is moved forwardly or toward the sliding frame so that the lower end of the threaded rod can be positioned directly on top of said bearing block 19.

By means of hand wheel 34, the threaded rod is now manipulated so that it will move downwardly through rail 31 and as this operation is continued, the lower end of the threaded rod will bear on bearing block 19 that is positioned on the upper end of the sliding frame, and consequently the latter becomes a supporting member for the motor truck and which latter is lifted until its wheels clear the tops of the track rails. The entire motor car and parts carried thereby is thus supported on a single bearing, namely, the foot plate 23, and while thus elevated, the motor car must necessarily be held in a steady position by the operator to prevent its tilting in one direction or another. While thus elevated and 65 with the wheels above the track rails, the

motor car can be turned end for end so as to reverse its position upon the track or it may be turned part way around so as to position its wheels upon the rails of a crossing track and when brought to proper position the operator manipulates the screw rod so as to move the same upwardly through rail 31, thus permitting the motor car to gradually descend upon the sliding frame which constitutes the support until the 75 wheels of the truck are positioned upon the track rails.

In the event that it is desired to lock the lifting mechanism while the truck is in elevated position, this can be accomplished by 80 positioning the end of locking bolt 29 in the lower one of the apertures 27 in lifting rod 25.

Under normal conditions or while not in service, the sliding frame is carried so that 85 the foot plate 23 occupies a plane approximately eight inches above the surface of the road bed.

A lifting and swinging support for motor cars of my improved construction is comparatively simple, occupies comparatively little space upon the motor car, and provides simple and efficient means whereby the operator of the car can readily reverse the position of the car upon the track or shift 95 the position of said car so that it may be placed upon the rails of a crossing track.

It will be readily understood that minor changes in the size, form and construction of the various parts of my improved device 100 may be made and substituted for those herein shown and described, without departing from the spirit of my invention, the scope of which is set forth in the appended claims.

I claim:

1. The combination of a car, a member arranged to slide vertically thereon, fixed guideways on the car for said member, a lifting member movably mounted on said car and normally out of operative relation 110 to said vertically sliding member, and means for operating said lifting member when in engagement with said sliding member to raise said car.

2. The combination of a motor car, a manipulative member arranged to slide vertically thereon, fixed guideways on the car for said member, a rotatable bearing on the lower end of said sliding member, and a manipulative threaded member normally out 120 of engagement with said vertically sliding member and movably mounted on said motor car and arranged to be placed in operative engagement with said sliding member to lift the car on said rotatable bearing. 125

3. The combination of a motor car, a manipulative frame member arranged to slide vertically thereon, a rotatable bearing on the lower end of said sliding frame member, a manipulative jack-screw normally out 130

of engagement with and carried by said motor car and arranged to be placed in operative engagement with said sliding frame member to lift the car on said rotatable bearing, and a collar on said jack-screw for adjustably limiting the lifting movement of said threaded member.

4. The combination of a car, vertical channel bars mounted thereon, a manually operable member arranged for vertical movement in said channel bars, flanged members connected to said channel bars, a transversely disposed horizontal sliding bar

mounted between said flanged members, a manipulative threaded member mounted in 15 said horizontal sliding bar and adapted to be moved into engagement with said vertically sliding member, and a rotatable bearing mounted on the lower end of said vertically sliding member, said bearing being below the approximate center of gravity of the entire car.

In testimony whereof I hereunto affix my signature this 27th day of October, 1919.

JOSEPH E. LOEFFLER.
